Gasport, N.Y. 10605

Filed Apr. 26, 1967, Ser. No. 6,849

Term of patent 7 years

(Cl. D34—5)

FIG. 1 is a top plan view of a swing seat, showing my new design;

FIG. 2 is a side elevational view thereof;

FIG. 3 is an end elevational view thereof;

FIG. 4 is a fragmentary bottom plan view showing one end portion thereof;

FIG. 5 is a transverse sectional view thereof taken about on line V-V of FIG. 1;

FIG. 6 is a transverse sectional view thereof taken about on line VI-VI of FIG. 1; and

FIG. 7 is a fragmentary, transverse sectional view thereof taken about as indicated by line VII of FIG. 1.

The bottom portion not shown is identical to the portion shown in FIG. 4, and the side and end not shown are identical to the side and end shown in FIGS. 2 and 3 respectively.

I claim:

The ornamental design for a swing seat or similar article, substantially as shown and described.
